UNITED STATES PATENT OFFICE.

VICTOR G. MOSS, OF CLEVELAND, OHIO, ASSIGNEE TO THE CHAMPION REGISTER COMPANY, OF CLEVELAND, OHIO, A CORPORATION OF OHIO.

REEL FOR CLOTHESLINES AND THE LIKE.

Application filed December 14, 1922. Serial No. 608,810.

To all whom it may concern:

Be it known that I, VICTOR G. MOSS, a citizen of the United States, and a resident of Cleveland, county of Cuyahoga, and State 5 of Ohio, have invented a new and useful Improvement in Reels for Clotheslines and the like, of which the following is a specification, the principle of the invention being herein explained and the best mode in which 10 I have contemplated applying that principle, so as to distinguish it from other inventions.

The present improvements relate to a clothesline holder on the order of a reel or spool where the clothesline or other cable or 15 wire may be conveniently wound and in turn unwound therefrom. The object of the invention is to provide a simple and compact device of this sort which will permit a line to be thus wound or unwound without becoming either tangled or twisted. Another 20 object is to construct such reel so that the parts may be nested together for shipment in much less space than would be required were the devices assembled, the assembly of 25 the parts, however, being a very simple matter requiring no special proof.

To the accomplishment of the foregoing and related ends, the invention, then, consists of the means hereinafter fully described 30 and particularly pointed out in the claims, the annexed drawing and the following description setting forth in detail certain mechanism embodying the invention, such disclosed means constituting, however, but 35 one of various mechanical forms in which the principle of the invention may be used.

In said annexed drawing:—

Fig. 1 is a perspective view of my improved reel or holder; Fig. 2 is a central 40 axial section thereof; Fig. 3 illustrates the manner in which the parts of the device may be nested together for shipment; and Fig. 4 is a partial longitudinal section of a modified form of my reel showing the disks assembled in spaced-apart relation.

As clearly shown in the aforesaid drawing, my improved holder consists in effect of two similar disks 1, each provided with a peripheral outwardly flaring flange 2, the 50 edges of which are reinforced by being turned over to form a bead 3. In assembling the device, such two disks are secured together with the flanges thereof extending in opposite directions (see Fig. 2), as the result of which a reel or spool having a V-

shaped space 4 for the reception of the line is obviously provided.

The disks are thus secured together by means of bolts 5 that at the same time carry handles 6. Said bolts pass through diametrically opposed holes 7 in the disks and the portions thereof that carry the handles 6 extend in opposite directions so that the user may readily grasp one handle in each hand. Nuts 8 and 9 on the inner threaded ends of 65 the bolts serve to secure the same in such holes 7 in the disks, at the same time clamping the latter firmly together and by proper adjustment of said bolt 8 leaving the handles 6 freely rotatable on the projecting portions 70 of the bolts.

For the purpose of shipment and storage, the disks may be stacked or nested, as shown in Fig. 3, with the flanges 2 all disposed in the same direction. It will thus be seen 75 that a large number of reels or holders will occupy a relatively small space compared with the space that would be required were they packed in assembled condition.

If desired, in order to increase the capacity of the reel, the disks may be assembled in spaced-apart relation as shown in Fig. 4, instead of being clamped with their opposed faces directly in contact with each other. This merely involves lengthening the 80 bolts 10, that correspond with bolts 5, and the insertion of spacing means between such disk-faces. Such spacing means conveniently take the form of sleeves or ferrules 11 surrounding said bolts 10, two or more additional shorter bolts 12 with similar ferrules 90 being spaced equidistantly about the periphery of the disks.

Other modes of applying the principle of my invention may be employed instead of 95 the one explained, change being made as regards the mechanism herein disclosed, provided the means stated by any of the following claims or the equivalent of such stated means be employed.

I therefore particularly point out and distinctly claim as my invention:—

1. In a device of the character described, the combination of two similar disks, each provided with a peripheral outwardly flaring flange, said disks each having two diametrically opposed holes and being placed together with corresponding holes in register and with the flanges thereof extending in opposite directions; bolts passing through 105 110

such registering holes and clamping said disks together, said bolts extending in opposite directions from said disks; and handles rotatively mounted on said bolts, respectively.

2. In a device of the character described, the combination of two similar disks, each provided with a peripheral outwardly flaring flange, said disks each having two diametrically opposed holes and being placed together with corresponding holes in register and with the flanges thereof extending in opposite directions; bolts passing through

such registering holes, said bolts extending in opposite directions from said disks; two nuts on each bolt lying on opposite sides of said disks and serving to clamp the same together; and handles rotatively mounted in said bolts, respectively, each handle being held between the head of the corresponding bolt and the nut on the adjacent side of said disks.

Signed by me, this 11th day of December, 1922.

VICTOR G. MOSS.
